UNITED STATES PATENT OFFICE.

WILLARD I. LEWIS, OF WALPOLE, MASSACHUSETTS.

CLOTH-FOLDING MACHINE.

Application filed May 31, 1922. Serial No. 564,803.

To all whom it may concern:

Be it known that I, WILLARD I. LEWIS, a citizen of the United States, residing at Walpole, in the county of Norfolk, State of Massachusetts, have invented a certain new and useful Improvement in Cloth-Folding Machines, of which the following is a specification, reference being had therein to the accompanying drawings.

10 My invention relates to cloth-folding machines, and in particular to the means employed in a machine of such class for operating the movable jaws of the pairs of fold-holding jaws that are located at the opposite 15 sides of the table on which the cloth is folded.

One main object of the invention is to provide improved means for applying and controlling the pressure by which the respective pairs of jaws are closed upon the folds. I attain this object by providing power pressure devices and a novel organization of parts for controlling and transmitting the pressure, etc. A preferred mode 25 of carrying this object into effect is by means of fluid-pressure, for instance by compressed air.

Another main object of the invention is to provide an improved manner for relieving at the respective sides of the folding table, alternately, the grasping pressure of the pair of jaws between which a fold is to be inserted, to facilitate the entrance of a folding blade and the newly formed fold 35 between the said jaws. I attain such object by providing novel relief means. A preferred mode of carrying this object into effect is by utilizing for the purpose of slightly separating the jaws of the pair at 40 either side of the table, the movable jaw of the pair at the other side as a fulcrum or abutment, and vice versa.

An illustrative embodiment of the features of the invention is shown in the accompanying drawings, in which latter,—

Fig. 1 is a view of a cloth-folding machine of a well-known type in extensive use containing the said illustrative embodiment, the view being in section on line 1, 1, of Fig. 2.

Fig. 2 is a plan view thereof, with the table and the parts above the table omitted.

Fig. 3 is a view looking from the right-hand side in Figs. 1 and 2, showing chiefly 55 the pressure organization of said figures.

The machine shown in the drawings comprises, as usual, opposite stationary jaws 5, 5, and an intermediate vertically movable folding table 4 having combined with the opposite edges thereof movable jaws 6, 6, 60 which co-act with the stationary jaws 5, 5, in holding the folds at the ends of the layers 3^a of cloth which are laid upon the said table. The machine comprises also, a pair of folding blades mounted upon the upper ends of radius arms 21, 21, swinging around pivotal centers at their lower ends, with the said radius arms operatively connected by means of connecting rods 19, 19, 65 with cranks 20, 20, on an actuating shaft 70 2, whereby the folding blades are reciprocated back and forth above the table, in this instance all being as usual. The said pair of folding blades have combined therewith, as usual, rods 22, 22, working in guide-sleeves 221, 221, which are pivotally mounted in an elevated position upon upstanding brackets 229, 229, rising from the main frame of the machine. The said rods and 75 guide-sleeves control the pair of folding blades in well-known manner by causing the blades to rock as they are carried back and forth above the table 4, so as to cause them to act alternately in pushing folds of the cloth π in between the jaws of the pairs 80 of jaws at the opposite sides of the table. 85

In this illustrative embodiment, the respective movable jaws 6, 6, substantially as heretofore, are connected by means of links 35, 35, to arms 34, 34, fixed on rockshafts 90 33, 33, located below the said jaws, one jaw 6 being connected by means of certain of such links with the arms 34, 34, of one of the said rockshafts, and the other jaw 6 being connected by certain of the links with 95 the arms of the other rockshaft. The connection of the links 35, 35, with the movable jaws 6, 6, is effected in this instance through pivotal engagement of the upper ends of such links with brackets 36, 36, attached to 100 said jaws.

In the place of the strong springs which in machines heretofore in use in the art are combined with the respective rockshafts, for the purpose of pressing the table upward 105 and causing the movable jaws to be pressed toward the stationary ones, and of the cam-actuated pawl and ratchet mechanism employed in such machines for relieving the pressure of the movable jaws alternately, 110

I employ mechanism embodying the principles of the invention, as follows:

A fixed arm 32 of one rockshaft 33 is connected by means of a link 31 with an upstanding arm of a bell-crank 24, and a similar arm 32 of the other rockshaft is connected by a link 31 with an upstanding arm of a bell-crank 25. The bell-cranks 24, 25, and the connections between the same and the movable jaws 6, 6, serve primarily for the transmission of power, applied to such bell-cranks, to the movable jaws 6, 6, to urge them toward the stationary jaws 5, 5. They serve secondarily in relieving the pressure of the said movable jaws toward the said stationary jaws.

The means and manner of applying power to the bell-cranks for the upholding of the table 4 and the production of the pressure of the movable jaws 6, 6, may vary in practice, in the case of the broader phases of the invention. In accordance with one part of the invention I utilize a single source of pressure. In the present instance, fluid-pressure means is provided, comprising a cylinder 8 containing a piston 7 that is connected by means of a rod 17 with horizontal arms of the bell-cranks 24, 25. The upper end of the rod 17 carries a pin 23 engaging the said arms, one of the latter being longitudinally slotted as shown in Fig. 1 to permit the sliding play which is necessary in order to compensate for the opposite curvature of the arcs in which the two arms vibrate. When pressure is admitted into the cylinder 8 behind (below) the piston 7, it is transmitted by rod 17 to the bell cranks, and from the latter through the intermediate parts to which reference has been made to the movable jaws 6, 6, at opposite edges of table 4.

The fluid pressure medium which is employed preferably is compressed air. The fluid-pressure medium is supplied to the cylinder through a pipe 12 communicating with the lower end of the cylinder, the flow of air being controlled by means of a three-way valve 9 having a rotating valve-member. For the manual actuation of the said valve-member, I provide the valve-member with a valve-lever 10, and connect the latter by means of a rod 11 with a manually operated member, which in this instance is an upstanding arm 13 on a rock-shaft 14 having connected therewith a treadle 15. When treadle 15 is pressed down, the rotating valve-member thereby is actuated to admit air below the piston, to produce the required pressure of the movable jaws. A fixed detent piece 16 is provided alongside the treadle so that the latter, after being depressed, may be shifted sidewise under the shoulder of the detent, and will be held thereby to keep the valve open and maintain the air pressure. When the treadle is pushed by the operator

sidewise out of engagement with the shoulder of the detent 16, a spring 18 will actuate the parts, including the rotating valve-member, reversely so as to shut off and relieve the air pressure, and thereby relieve the pressure entirely at both pairs of jaws, allowing the latter and the table to descend. This action provides for the lowering of the table for the removal of folded cloth therefrom. Subsequent raising of the table again is effected, without any exertion or strain on the operator, when treadle 15 is depressed by the foot of the operator so as to admit air to the cylinder below the piston.

The utilization of air as a pressure-applying medium secures an elastic or yielding action which, without the use of springs, enables the movable jaws 6, 6, and the table 4 to accommodate themselves to the growing thickness of the succession of folds introduced between the movable and fixed jaws as the folding process proceeds.

Referring now to the relief action; that is to say, to the action by which the pressure of the movable jaws toward the stationary ones with which they respectively cooperate is relieved, so as to facilitate the entrance of a folding blade and a cloth-fold between a movable jaw and the companion stationary one.—

This relief action is provided for by means independent of the folding means for effecting alternate application of the said pressure and relief thereof at the opposite pairs of jaws in proper correlation with the action of the folding means.

This portion of the invention is based upon the broad principles of utilizing either movable jaw, while it is in contact with the companion stationary jaw or the cloth-folds that are interposed between it and such stationary jaw, as a fulcrum or abutment for the parts more immediately involved in relieving the pressure of the opposite movable jaw from the corresponding stationary jaw or the interposed cloth-folds. I have embodied such principle in the illustrative embodiment of the invention by arranging for movement bodily of the bell-cranks 24, 25, simultaneously with the folding movement of the folding blades, but in the opposite direction.

I secure the desired bodily movement of the bell-cranks by supporting the bell-crank pivots 26, 26, movably, and automatically causing movements of the said pivots whereby the required action is secured. The said pivots are located in the present instance at the upper ends of radius arms 30, 30, which in turn are mounted pivotally at their lower ends with capacity to swing in a direction at right angles with the length of the jaws. These radius arms are grouped in two pairs, one pair for the support of one bell-crank, and the other pair for the support of the

other bell-crank. The two pairs are connected together by means of side-bars 28, 29, so that both pairs swing in unison. The swinging movement is produced by means 5 of a cam 37 upon shaft 2, working between the branches of the forked upper end of an arm 38 rising from a supporting rockshaft 39 that is mounted in the lower portion of the machine frame. The said arm 38 has 10 connected to it at 40 one end of a link 41 having its other end connected at 42 to an extension of the side-bar 29, so that as the cam 37 swings the arm 38 the required movement is communicated from such arm 15 to the radius arms and bell-cranks.

This bodily movement of the bell-cranks in the direction opposite that of the stroke of the folding blades operates with the effect of causing the movable jaw of the pair 20 of jaws toward which the movement of the bell-cranks is made to take firmer bearing against the stationary jaw, and has the reflex action of relieving the pressure of the movable jaw of the pair of jaws toward 25 which the folding blades move.

Movement of the radius-arms and bell-cranks toward the left in Fig. 1 will act through bell-crank 24 and the connections to the left-hand movable jaw 6 to cause the 30 latter to take firm bearing, while the reflex actions from the firmly backed-up left-hand movable jaw through the said connections and bell-crank will operate to influence the bell-crank 25 and the connections therefrom 35 to the right-hand movable jaw 6 so as to pull the latter downward away from the adjacent stationary jaw, to facilitate the entrance of a folding blade 1 and cloth fold between the latter two jaws. Conversely, 40 bodily movement of the radius-arms and the bell-cranks supported thereby toward the right-hand side in Figs. 1 and 2 will reverse the action in the case of the respective pairs of jaws 5 and 6. In principle, 45 the pressure transmitting means comprises a lever-arrangement by which the pressure is transmitted along different lines to the respective pairs of jaws, and the cam 37, etc., constitute devices actuating the said 50 lever-arrangement to relieve the holding pressure at the opposite pairs of jaws alternately.

The illustrated construction and arrangement constitutes a mechanism in which the 55 jaw-operating pressure is transmitted along diverging lines to the respective pairs of jaws from the point of connection with the source of pressure. Also in which the transmitting means is actuated through devices connecting with such means at or adjacent the point of convergence of the lines referred to, to relieve the holding pressure at the opposite pairs of jaws alternately.

The employment of manually controlled 60 fluid-pressure devices in connection with the

movable jaws and folding table is of marked advantage. Not only is a yielding action of the movable jaws secured without the employment of springs, but by reason of the possibility of entirely relieving the pressure by opening the controlling valve, so as to permit the table to descend, the operator is relieved of the necessity existing in the case of machines at present in use for exerting considerable strength, as well as applying her full weight, to a treadle in order to depress it and thereby wind up the stiff springs which in such machines are employed to hold the movable jaws pressed toward their co-acting stationary jaws. A 70 strong and heavy operator is no longer required to operate cloth-folding machines, as my said fluid-pressure devices operate automatically at a light touch of the foot upon the controlling treadle. 75

The illustrated arrangement utilizes the conventional treadle now in use on cloth-folding machines, in order that my devices may be applied to such machines with the least departure from what the operators are 80 accustomed to; however, it is within the scope and contemplation of my invention to utilize any other suitable form of control for the flow of the fluid-pressure medium into and out of the cylinder 8. 85

Stated now in general terms, in its entirely my invention comprises a new and improved means of actuating the folding table from a single power-actuated source of pressure, (which in the present embodiment consists in a piston driven by compressed air, or it might be other fluid-pressure,) and novel means for effecting alternate application and relief of the pressure at the two 90 sides of the table in proper correlation with the action of the folding-blades; it also comprises controlling devices for governing the actuation of the folding table such that the said table may be lifted into its operating position or lowered into the position 95 necessary for the removal of the folded cloth without the exertion of any manual effort. 100

In the connection last mentioned, important considerations are that heretofore the operator of cloth-folding machines has been subject to strain, fatigue, and injurious effects resulting from having to reinstate at intervals, by manual effort the considerable 115 degree of spring tension by means of which the movable folding table is held against the cloth-engaging jaws, a relaxation of said spring tension being necessary from time to time in the course of a working day, in order to permit the table to descend, to provide for the removal of the accumulated layers of cloth piled thereon. After every such relaxation the spring tension has to be reinstated in order to provide for further 120 folding, and this resetting has required the 125 130

manual actuation of a lever or treadle which is so combined and connected with the said springs that its movement will increase the spring tension. Through the devices of my invention, I relieve the operator of a cloth folding machine of the usual strain and fatigue due to the hitherto unavoidable muscular effort involved, in virtue of my combination, with the movable folding table, of power-driven automatic means for raising the table and producing the proper degree of working pressure upon the cloth-folds, the said means having capacity for relaxation of such pressure at the required times, and a controlling-device through which the operator may at will call the said power-driven automatic means into action to produce such pressure.

I show and describe herein an illustrative embodiment of the invention comprising fluid-pressure devices; while the use of fluid-pressure has practical advantages, the invention in some of its phases is not restricted to these precise devices or to the employment of fluid-pressure.

The invention, in its broader phases, is not restricted to the particular mode of embodiment shown in the drawings hereof.

What is claimed as the invention is,—

1. In a cloth-folding machine, the combination with oppositely-located stationary cloth-retaining jaws, and movable cloth-retaining jaws cooperating with the stationary jaws, of a single fluid-pressure actuated source of pressure, and trains of transmitting devices extending separately to the respective movable jaws so as to press them yieldingly toward the stationary ones.

2. In a cloth-folding machine, the combination with stationary cloth-retaining jaws and a movable table having cloth-retaining jaws, of a single power-driven source of pressure, means for transmitting such pressure to both ends of the table so as to press the said ends yieldingly toward the stationary holding jaws, and manually-controlled means for governing the said power-driven source of pressure to yieldingly uphold the table or lower the same, as required, at will.

3. In a cloth-folding machine, the combination with stationary cloth-retaining jaws and a movable table having cloth-retaining jaws, of a single fluid-pressure actuated source of pressure, means for transmitting such pressure to the table so as to press the movable jaws yieldingly toward the stationary holding jaws, and manually-controlled means for governing the fluid-pressure so as to yieldingly uphold the table or lower the same, as required, at will.

4. In a cloth-folding machine, the combination with folding blades, stationary cloth-retaining jaws, and movable cloth-retaining jaws, of a single source of pressure,

means for transmitting such pressure to both movable jaws so as to press them toward the fixed holding jaws, and means independent of the folding means for effecting alternate application and relief of the said pressure at the said two movable jaws in proper correlation with the action of the folding blades.

5. In a cloth-folding machine, the combination with folding means, stationary cloth-retaining jaws, and movable cloth-retaining jaws cooperating with the stationary jaws, of a single fluid-pressure actuated source of pressure, means for transmitting such pressure to both movable jaws so as to press them toward the stationary ones, and means independent of the folding means for effecting alternate application and relief of the said pressure at the opposite pairs of jaws, in proper correlation with the action of the folding means.

6. In a cloth-folding machine, the combination with folding blades, opposite stationary jaws, a movable table having cloth-retaining jaws, and a single power-actuated source of pressure of means for transmitting such pressure to close the respective movable jaws upon the cloth-folds, means independent of the folding means for effecting alternate application and relief of the pressure at the respective pairs of jaws in proper correlation with the action of the folding blades, and manually-controlled means for governing the said power-actuated source of pressure to raise and lower the table at will.

7. In a cloth-folding machine, the combination with folding blades, opposite pairs of stationary and movable cloth-holding jaws, and devices for applying pressure to bear the movable jaws toward the stationary ones, of means actuating such devices to utilize each movable jaw in turn as a fulcrum or abutment relative to which said devices are operated to relieve the holding pressure of the opposite movable jaw.

8. In a cloth-folding machine, the combination with folding blades, opposite pairs of fold-holding jaws, a single source of pressure, and means through which the pressure acts equally in closing both pairs of jaws, of means actuating the pressure-transmitting means to utilize jaws of the respective pairs alternately as fulcras or abutments relative to which said transmitting means is operated to relieve the holding pressure of the opposite pair of jaws.

9. In a cloth-folding machine, the combination with folding blades, and opposite pairs of fold-holding jaws, of a source of pressure, transmitting means through which the pressure is transmitted along diverging lines to the respective pairs of jaws, and devices actuating the said means through connection at or adjacent the point of con-

vergence of such lines to relieve the holding pressure at the opposite pairs of jaws alternately.

10. In a cloth-folding machine, the combination with folding blades, opposite pairs of stationary and movable cloth-holding jaws, and a source of pressure, of devices for transmitting pressure along diverging lines to the movable jaws of the respective 5 pairs of jaws, and means actuating such devices through connection at or adjacent the point of convergence of such lines to utilize each movable jaw in turn as a fulcrum or abutment relative to which said devices are 10 operated to relieve the holding pressure of the opposite movable jaw.
11. In a cloth-folding machine, the combination with folding blades, and opposite pairs of fold-holding jaws, of a source of 20 pressure, and transmitting means comprising a lever-arrangement by which the pressure is transmitted along different lines to the respective pairs of jaws, and devices actuating the said lever-arrangement to relieve the holding pressure at the opposite 25 pairs of jaws alternately.

12. In a cloth-folding machine, the combination with folding blades, and opposite pairs of fold-holding jaws, of a source of pressure, paired bell-cranks to which the 30 pressure is transmitted, connections from the respective bell-cranks to the respective pairs of jaws, movable supporting means for the bell-cranks, and means for actuating said supporting means to relieve the jaw-pressure of the respective pairs alternately. 35

13. In a cloth-folding machine, the combination with folding blades, opposite pairs of fold-holding jaws, and jaw-operating rockshafts, of paired bell-cranks 40 operatively connected with the said rockshafts, a source of pressure connected with said bell-cranks, a movable support for the bell-cranks, and means for actuating said support to relieve the jaw-pressure of the respective pairs of jaws alternately. 45

In testimony whereof I affix my signature in presence of two witnesses.

WILLARD I. LEWIS.
